UNITED STATES PATENT OFFICE.

JOHN WALTER BRADLEY, OF BRADFORD, COUNTY OF YORK, ENGLAND.

CIRCULAR COMBING MACHINE.

SPECIFICATION forming part of Letters Patent No. 357,171, dated February 8, 1887.

Application filed May 18, 1886. Serial No. 202,583. (No model.)

To all whom it may concern:

Be it known that I, JOHN WALTER BRADLEY, a subject of the Queen of Great Britain, residing at Bradford, in the county of York, England, have invented new and useful Improvements in Circular Combing Machines, of which the following is a specification.

This invention consists in further improvements upon an invention for which Letters 10 Patent of the United States were applied for on or about September 23, 1884, Serial No. 143,807, and November 13, 1884, Serial No. 147,824, respectively, the present improvements having for their object to provide an 15 improved jaw for holding the sliver and giving to it the necessary tension immediately before it is delivered to the combs, an improved means of feeding the required length of sliver at each revolution of the feed-drum, and an im- 20 proved means of regulating the relative speeds of the circular combs and the feed-drum to prevent the oblique dragging of the sliver.

In carrying out my invention the balls of sliver are supported in arms and upon rollers 25 mounted in the arms at the top part of the machine. Each sliver passes down behind circular guide-rails which surround the feed-drum, and from thence through a hole in the top of the tension-jaw. The sliver then passes 30 under a brass rail and then under the jaw, where it is nipped between the under surface of the jaw and the upper surface of a bearer, to which the jaw is jointed. The sliver im- 35 mediately after passing between the jaw and the bearer is delivered to the combs in a per- fectly flat fan-shaped fringe. The bearer which carries the tension-jaw is jointed to a flange connected to a boss which drives the feed-drum, and the bearer is caused to rise at the required 40 part of its revolution by means of a bridge or inclined bar or bars fixed at a suitable angle, and over which bar or bars the bearers travel in their revolution. As the bearers pass up the incline the sliver is pulled down from the 45 creel by means of the curved feed-bar, which holds down the end of the sliver as the ten- sion-jaw and the bearer are rising. The sliver after passing the feed-bar is plowed out of the combs by means of pointed knives fixed 50 between each circular row of pins, and the fringe of sliver then passes over a dead-plate

to the dabbing-brush, at which point the larger and smaller circular combs are almost in contact. At this point the bearers upon which the jaws are mounted drop off the end of the bridge or curved bar, which here terminates, and as the end of the sliver is held between the jaw and the bearer this latter, in dropping, pulls down a portion of sliver from the creels and thereby assists in feeding the required 60 length of sliver.

In order to prevent the sliver from dragging or being pulled back obliquely between the feed-drum and the combs, the gearing beneath the combing-table which drives the circular 65 combs and the feed-drums is so speeded that the combs are driven rather faster than the feed apparatus, whereby the tendency to drag the sliver is compensated for and the sliver is delivered to the combs in true radial lines. 70 The dabbing-brush is driven in the ordinary way.

In order to enable my invention to be fully understood, I will proceed to describe the same by reference to the accompanying drawings, in 75 which—

Figure 1 represents a sectional elevation of a combing-machine constructed according to my invention. Fig. 2 represents a plan of the same with the feed-drum removed. Fig. 2* 80 represents a side elevation of the star-wheel separator. Fig. 3 represents a perspective view, enlarged, of one of the tension-jaws and bearers. Fig. 4 is a front view of one of the tension-jaws. Fig. 5 is a plan of the combing-table, showing the bridge or curved bars upon which the bearers travel during part of their revolution, and which may be adjusted to give the bearers the required rise or elevation, and also showing the toothed rim and its driv- 85 ing-pinion. Fig. 5* represents a detail view of the bridge or curved bar and its means of adjustment, and Fig. 6 represents a plan of the gearing beneath the combing-table, which is driven by the main driving-shaft and actu- 90 ates the two circular combs and the feed-drum. 95

Similar letters refer to similar parts in all the figures.

The larger and smaller circular combs, A and B, respectively, are caused to revolve upon 100 steam-chests C and D. The large comb, A, is driven by means of a rack of internal teeth, E,

into which is geared a pinion, 1, actuated by the gearing A^2 beneath the combing-table, and the smaller or internal circular comb is driven by means of a rack of external teeth, F, which are also driven from said gearing A^2 beneath the table.

The broad lower flange, J, of the drum G is mounted upon a rim, K, having a toothed internal periphery, L, and revolving upon the circle M. Upon the bearers N are jointed the tension-jaws P, and these bearers are hinged to the top flange, H, of the drum G, and are carried round with the drum as it rotates. A projection at the bottom of the bearer N rests upon the circle O, upon which it travels during part of its revolution. The lower part of said bearer during the remainder of each revolution of the drum rests or travels upon the bridge or curved bar Q, which is, by means of set-screws 2, adjusted and fixed at the required angle to cause the bearers N to rise to the necessary height, so that a sufficient quantity of the sliver R may be pulled through the opening between the jaws P and the bearers N, at which opening the sliver is nipped by the weight of the jaw P.

The sliver R passes down behind the guide S, which is fixed to the periphery of the feed-drum U, secured to the shaft W, which feed-drum is driven by means of an arm, 3, attached to said shaft, and an upright spindle, V, working in a hole, 4, in said arm, which spindle is fixed to the flange H. The sliver then passes through the opening in the arched top of the jaw P, and under a circular rail, T, which rail is supported by uprights and brackets to the flange J. After passing under the rail T the sliver is drawn under the outer weighted end of the jaw P, from whence it passes direct to the combs. This rail T is for the purpose of giving the sliver the proper tension before it reaches the combs, and also for holding said sliver off from the weighted end of the jaw and from the combs, to prevent said sliver from either slackening or being drawn back, and thereby preventing an irregular feed.

During the revolution of the feed-drum the ends of the fringe of sliver projecting from the nip of the jaws P are caught under the curved feed-bar X, Fig. 2, and as the bearers are at that time traveling up the incline of the bridge Q a certain regulated portion of the sliver is pulled from under the jaw P, the weight of which jaw gives the required tension to the sliver. The fringe thus pulled out is lifted out of the inner comb by means of pointed knives in the ordinary manner, then passes over the dead-plate Y to the dabbing-brush Z, where the fibers are dabbed into the teeth of both circular combs, which come together at a point beneath the dabbing-brush. After the bearers N and the tension-jaws P have passed the dabbing-brush Z the sliver then contained in the combs is separated between the combs by means of a star-wheel, 5, Figs. 2 and 2*, and at this point the bearers drop off the end

of the bridge or curved bar Q, and thereby pull down a regulated length of sliver R from the balls at the top of the feed-drum.

The two circular combs A and B are driven from the gearing A^2 , and the drum U of the feed apparatus is driven from the gearing 6.

The two circular combs A and B are driven at the same surface-speed—that is, so that they will both complete one revolution at the same moment. The speed at which the combs A and B are revolved is a little faster than the speed at which the drum U of the feed apparatus and the bearers with their tension-jaws are caused to revolve. This greater speed of the combs over that of the bearers and jaws prevents the fringe of sliver from dragging or being held back obliquely after the sliver has been plowed out of the comb and when it lies loosely upon the dead-plate Y. The greater speed of the combs over that of the feed-drum will overcome this tendency of the sliver to drag, and thus cause the same to be delivered to the combs in true radial lines.

The circular combs A and B receive motion from the vertical shaft C, which passes through the table D' of the machine and drives the combs by means of gearing F', mounted upon the upper side of the table. The bearers N, carrying the tension-jaws P, with the feed-drum and its flanges H and J, are driven by a pinion, E', fixed upon the upper end of the shaft E', which pinion gears into the internal teeth, L.

The gearing A^2 , which drives the two circular combs A and B and the feed-drum G, is actuated by a vertical shaft, B', which is driven by means of the bevel-wheels B' from the main shaft A'.

The dabbing-brush Z is fixed to the upright shaft G', which works in brass bushes fixed to the upright frame H'. The upright shaft G' is given a reciprocating motion by means of the pulley C', spindle L', eccentric K, and eccentric-rod r, one end of which is fitted to the eccentric and the other end is jointed to a stud fixed upon the shaft G'.

The grooved wheel C' on the eccentric-spindle L' is driven by means of a cord, D', from the grooved wheel M', fixed upon the main shaft A'. The fast and loose pulleys upon the main shaft are represented at N' and O', respectively, in Fig. 6.

Having now particularly described and ascertained the nature of the said invention and in what manner the same is to be performed, I declare that what I claim is—

1. The combination, with the bearers N, of the tension-jaws P, hinged to said bearers and formed with open tops, substantially as shown and described.

2. The combination, with the bearers N, of the tension-jaws P, hinged to said bearers and formed with open tops, and the tension-rail T, substantially as shown and described.

3. The combination, with the bridge or curved bar or bars Q, and means for vertically

adjusting the same, of the bearers N, open-top jaws P, and the feed-bar X, which holds down the ends of the sliver while the bearers and jaws are ascending the bridge, all substantially 5 as shown and described.

4. The combination, with two circular combs and means for driving the same at the same surface-speed, of a feed-drum, bearers, and tension-jaws, and means whereby the said 10 drum, bearers, and jaws are caused to revolve at a slower rate of speed than that of the combs, for the purpose of avoiding the dragging back of the ends of the sliver, and causing such ends to lie in true radial lines across the combs, 15 substantially as herein described.

5. In combination, the open-top bearers N, the tension-jaws P, hinged to said bearers at their rear ends, the bar or bars Q, means for vertically adjusting the same, and the feed-bar

X, substantially as and for the purposes set 20 forth.

6. In combination, the tension-jaws P, bearers N, bar or bars Q, means for vertically adjusting the same, feed-bar X, two circular combs, one within the other, means for driving 25 the same, the feed apparatus, and means for driving the same at a speed somewhat slower than that of the combs, substantially as set forth.

7. In combination with the jaw P, bearer N, 30 means for imparting vertical movement to said jaw and bearer, the inner and outer combs, A and B, and the tension-rail T, all substantially as shown, and for the purposes described.

JOHN WALTER BRADLEY.
